UNITED STATES PATENT OFFICE

149,521

DESIGN FOR A HAT

Charles Silbermann, Saint-Mande, France

Application April 12, 1945, Serial No. 118,970
In France December 19, 1942

Section 1, Public Law 690, August 8, 1946

Term of patent 14 years

(Cl. D3—13)

To all whom it may concern:

Be it known that I, Charles Silbermann, a citizen of the French Republic, residing at Saint-Mande, (Seine) France, have invented a new, original, and ornamental Design for a Hat, of which the following is a specification, reference being had to the accompanying drawings, forming part thereof.

Fig. 1 is a side perspective view of a hat, showing my new design, and

Fig. 2 is a front perspective view of the hat shown in Fig. 1.

I claim:

The ornamental design for a hat, as shown.

CHARLES SILBERMANN.
